UNITED STATES PATENT OFFICE.

OSCAR P. BENJAMIN, OF DETROIT, MICHIGAN, ASSIGNOR TO CAPITOL BRASS WORKS, OF DETROIT, MICHIGAN, A CORPORATION OF MICHIGAN.

BATH COCK.

Application filed May 31, 1921. Serial No. 473,790.

To all whom it may concern:

Be it known that I, OSCAR P. BENJAMIN, a citizen of the United States of America, residing at Detroit, in the county of Wayne and State of Michigan, have invented certain new and useful Improvements in Bath Cocks, of which the following is a specification, reference being had therein to the accompanying drawings.

10 This invention relates to bath cocks and that class of faucets, spigots or outlet members, from which different kinds of liquids may be discharged.

15 The primary object of my invention is to provide a cock with a novel mixing chamber which affords a quick control over the uniformity of temperature in the flow of water or other liquid from the cock.

20 Another object of this invention is to provide a bath cock having a chamber common to connections established with the bath cock, said chamber having a common outlet and deflectors or baffles therein which cause liquid from the connections to commingle 25 before being discharged from the chamber.

25 A further object of my invention is to furnish a bath cock with the mixing chamber which will contribute to an artistic design of the cock and the location of the 30 chamber in no manner whatsoever interferes with the operation of either valve of the cock.

35 The above and other objects are attained by a cock construction which permits of desired proportions of hot and cold water being mixed for a desired degree of temperature, and the construction entering into the cock will be hereinafter described and then claimed.

40 Reference will now be had to the drawing, wherein—

Figure 1 is a plan of the bath cock, partly broken away and partly in a horizontal section;

45 Fig. 2 is a front elevation of the same partly broken away and partly in longitudinal section, and

Fig. 3 is a central cross sectional view of the bath cock.

50 In the drawing, the reference numeral 1 denotes a back plate with the ends thereof substantially circular in front elevation and the intermediate portion of said plate is provided with a raised or vertical portion 2.

55 On the rear face of the back plate 1, con-

centric with the circular ends thereof, are connections 3 communicating with openings 4 in the back plate, said connections permitting of the bath cock being attached to the wall of a bath tub, basin, sink, or other structure, and also to pipes or conduits adapted to supply hot and cold water to the bath cock.

On the front face of the back plate 1, at the ends thereof, are outwardly extending frusto-conical shaped valve bodies 5 and 6 communicating with the openings 4 in the back plate 1 to receive water therefrom. The valve bodies 5 and 6 are provided with adjustable valve stems 7 and stuffing boxes 8 through which the valve stems operate, said stuffing boxes being of a conventional form harmonizing with the finish of the bath cock and insuring a non-leakable connection between the valve bodies and the adjustable valve stems.

On the outer ends of the valve stems 7 are cranks or handles 9 of a conventional form and on the inner ends of the adjustable valve stems 7 are valvular members 10 adapted to seat at the marginal edges of the openings 4 and close said openings.

The confronting or inner side walls of the valve body 5 are integral with a mixing chamber 11 which is formed by a vertical enlargement or shell 12 carried by the back plate 1 and the vertical portion 2 thereof, said mixing chamber being in the form of a pocket in said wall 12 communicating with the valve bodies 5 and 6 by lateral passages 13. The enlargement or shell 12 has a shape which contributes to the general appearance of the bath cock and the lower end of the enlargement or shell 12 has a discharge nozzle 14 or outlet opening to which is opposed the pocket in the wall 12 and to which outlet may be connected a nipple 15, hose coupling, or any other outlet device.

In the passages 13, between the mixing chamber 11 and the valve bodies 5 and 6, are upwardly inclined deflectors 16 extending at an angle in the direction of the top wall of the mixing chamber 11, said deflectors providing transverse partitions integral with the side walls and bottom walls of the passages 13 and thus reinforcing the enlargement or shell 12 at its juncture with the valve bodies 5 and 6.

Assuming that the valves of the bath cock

are open, the water admitted to the valve bodies 5 and 6 will impinge against the deflectors 16 and be deflected upwardly to the top wall of the mixing chamber where 5 the water will commingle and be deflected to the bottom of the mixing chamber and pass out of the discharge nozzle 14. It is therefore apparent that in causing the water to be discharged upwardly in two 10 opposed streams that the water thoroughly mixes before reaching the discharge nozzle and consequently it is possible to maintain a desired admixture, as to temperature, when one valve body is supplied with hot 15 water and the other with cold water. The uniform admixture can also be maintained with other liquids for purposes other than a uniform temperature, and it is practically impossible for one liquid to flow from the 20 cock without commingling with the other liquid when both valves are open or even approximately so. Ordinary city water pressure will be sufficient to cause the water to commingle in the mixing chamber and 25 maintain an aqueous curtain or body therein and since the bottom of the mixing chamber is somewhat contracted, it is obvious that liquids within the chamber and admitted thereto under pressure must thoroughly 30 commingle before being discharged.

The mixing chamber being located between the valve bodies lends itself to an artistic design of bath cock and I would have it understood that two or more valve 35 bodies may communicate with the mixing chamber; that various types of valves may

be used, and that the general arrangement and design of the structural element entering into the bath cock may be varied, without departing from the spirit of the invention as defined by the appended claims. 40

What I claim is:

1. A cock comprising horizontally disposed valve bodies, a mixing chamber connecting said valve bodies and extending to a plane above said valve bodies and having a depending outlet, and deflectors between said valve bodies and the outlet of said mixing chamber extending upwardly and inwardly away from said outlet and causing liquid to commingle at a point substantially removed from said outlet and be thereafter deflected downwardly to the depending outlet of said mixing chamber. 50

2. In a faucet wherein liquids are adapted to commingle centrally of the faucet and discharge through an outlet in the bottom wall of the faucet; a mixing pocket in the upper wall of said faucet opposed to said outlet, deflectors for directing the liquid 55 towards the top of the faucet, said deflectors extending upwardly at an inclination from the bottom wall of the faucet adjacent the outlet thereof with the upper ends of the deflectors closer to the axis of the faucet 60 outlet than the lower ends of said deflectors. 65

In testimony whereof I affix my signature in presence of two witnesses.

OSCAR P. BENJAMIN.
